UNITED STATES PATENT OFFICE.

ALBERT J. SLADE, JR., OF PEARL RIVER, NEW YORK, ASSIGNOR TO DEXTER FOLDER COMPANY, OF PEARL RIVER, NEW YORK, A CORPORATION OF NEW YORK.

DELIVERY TRIP MECHANISM.

1,108,802.

Specification of Letters Patent. Patented Aug. 25, 1914.

Application filed August 21, 1913. Serial No. 785,928.

To all whom it may concern:

Be it known that I, ALBERT J. SLADE, Jr., a citizen of the United States, and a resident of Pearl River, county of Rockland, 5 and State of New York, have invented certain new and useful Improvements in Delivery Trip Mechanism, of which the following is a full and clear specification.

This invention relates to mechanism for automatically stopping machines which operate on paper in the event of the paper becoming entangled or crumpled in such a way as to clog the action of the machine. Formerly, considerable waste of paper and not infrequent breakage of machinery, was occasioned by defects of this character, to overcome which, constituted the chief object of Patent No. 675,129, which was granted to Talbot C. Dexter on May 28th, 1901. According to the aforesaid patent, however, the throwout mechanism became effective only at predetermined times so that in the intervals between such times, the speed of the press or other machine was continued unabated until the ends of such intervals. With certain kinds of machines which operate on paper and especially in connection with printing presses, it is objectionable to delay the stoppage of the machine until the recurrence of a predetermined time for the reason that serious breakage may occur in the meanwhile. Thus in printing presses, it has happened not infrequently that the plate on the plate cylinder, became broken by the pressure due to a wad of paper formed by a crumpled sheet between the plate and impression cylinders.

The primary object of the present invention therefore, is to provide suitable and efficient means for making the throwout mechanism operate substantially instantaneously whenever a sheet of paper happens to become crumpled, thus avoiding broken platens and other injuries to the machine. Toward the attainment of this object, my invention contemplates the provision of suitable means adapted to be actuated by a crumpled or deranged sheet, which practically instantaneously connects the throwout mechanism with a continuously driven part, the result being that a retardation of the moving parts may be initiated at any instant whatever the positions of said moving parts may be.

Another object of this invention is to pro-

vide an improved device of this character which will embody simple mechanical details adapting the device to act positively and instantaneously.

Collateral and incidental advantages of the invention will appear in the specification, reference being had to the accompanying drawings in which the invention is exemplified in its adaptability to a rotary printing press.

In the drawings.—Figure 1 is a top plan view of one embodiment of my invention in its relations to a printing press, parts being broken away; Fig. 2 is a side elevation of the same, showing the parts in normal inactive position, and Fig. 3 is a similar side elevation showing the parts in shifted position due to the paper becoming crumpled or mussed.

In the following description and claims, the use of the term "crumpled" will be understood to indicate any crumpled or buckled condition of the paper which tends to make it become snagged or lodged during its passage over the feed board, or through the machine which is operating upon it, such for example as the printing press, of which parts are shown on the drawings.

According to the present embodiment of my invention, the ends of a bridge or cross-bar 1, are secured to the respective side frames 2 and 3 of the printing press, said bridge or cross-bar being provided with a stiffening rib 4. Projecting from this bridge or cross-bar are bracket arms 5 within the ends of which, is journaled a shaft 6, which is capable of being rocked to and fro under the impulse imparted by one or more fingers which depend therefrom. In the preferred embodiment, each of said fingers comprises a shank portion 7 which is keyed to the shaft 6, and a forwardly projecting portion 8 which is suitably formed to correspond to the machine part arranged adjacent thereto and over which the paper passes, such part in the present embodiment being the impression cylinder 9 of a printing press. Keyed to one end of the shaft 6 is a lever arm 10 from the lower end of which projects a pin 11, said pin being arranged to reciprocate in a slot 12 in the lower end of a connecting rod 13. The pin 11 and slot 12 constitute a lost motion joint in the mechanical train which connects the paper actuated fingers and a pawl 14, to which the upper

end of connecting rod 13 is pivotally connected at 15. The pawl 14 swings about a stud 16 carried by the depending arm 17 of a bell crank mounted on a stub shaft 18, the 5 upper arm 19 of the bell crank being pivotally connected at 20 with one end of a connecting rod 21. A spring 22 imparts a normal tendency to retain the pawl 14 in raised position with respect to a ratchet 10 wheel 23 which is keyed to a positively driven shaft 24, which is journaled in bearing brackets 25. In order to make the device operative in slowing down the press at any instant whatever the relative positions of 15 the parts, said shaft 24 is preferably rotated continuously. For this purpose, a gear 26 (see Fig. 1) is keyed to the shaft 24 on the opposite end to that on which the ratchet wheel 23 is keyed. Gear 26 meshes 20 with another gear 27 to which power is transmitted by a pinion 28 which may be driven in any suitable manner. The connecting rod 21 is pivotally connected at 29 to the upper arm 30 of a bent lever which 25 is pivoted on a stud 31. The lower arm 32 is pivotally connected at 33 to the forward end of a connecting rod 34 which operates a stop-mechanism of any suitable construction or throws a switch. 30 The operation of this embodiment of my invention is as follows. Under normal running conditions as the paper is being fed to the printing press, the space between the finger 8 and cylinder 9 is sufficient to permit 35 a sheet to pass if properly presented thereto. When, however, a sheet is interfered with in its passage, it naturally crumples and forces the finger 8 outwardly from the cylinder. By this movement, a clockwise oscillation is 40 imparted to the lever arm 10 which is transmitted to the pawl 14 by means of the connecting rod 13. As soon as the pawl 14 has been drawn into engagement with the ratchet wheel 23, the bell crank lever having 45 arms 17 and 19, is driven in a clockwise direction until the parts occupy the relative positions shown in Fig. 3 by an inspection

of which figure, it will be seen that pawl 14 has been revolved on its pivot at the same time that the connecting rod 34 has been thrown to operate the stop-mechanism. After said stop mechanism has been operated in this manner, the parts are retained in the positions shown in Fig. 3. According to this figure, the connecting rod performs the function of a strut and retains the lever arm in depressed position with the finger 8 in raised position. The parts may be returned to normal position by returning the pawl 14 to the position shown in Fig. 1.

What I claim is:

1. In a machine of the character described, a power transmitting member provided with teeth, a member for operating a stop mechanism for said machine, a pawl pivotally connected to said operating member, a tripping device adapted to permit the passage of an uncrumpled sheet and to be displaced by a crumpled sheet, and yieldable means adapted to normally retain said pawl away 7 from the toothed power-transmitting member, said tripping device being adapted to throw the pawl into engagement with said toothed member when displaced by a crumpled sheet. 75

2. The combination with a machine embodying a surface over which sheets of paper are passed, a power driven shaft, a ratchet carried by said shaft, a lever for operating a stop mechanism, a pawl carried by said lever, said pawl being normally retained out of engagement with said ratchet, a finger spaced from said surface to permit the passage of paper, said finger being displaceable under the action of crumpled 80 paper, and means connecting said finger to said pawl, said means being adapted to throw the pawl into engagement with the ratchet to effect the operation of said stop mechanism. 85
